UNITED STATES PATENT OFFICE.

OSCAR C. SCHROEDER, OF CHICAGO, ILLINOIS.

THERMOSTATICALLY-CONTROLLED MECHANISM.

Application filed September 22, 1923. Serial No. 664,307.

My invention relates, more particularly, to the thermostat element of thermostatically-operated mechanism, my invention having been devised for embodiment more particularly, though not exclusively, in burners. My primary objects are to provide a novel, simple and economical construction of thermostat; to provide for the automatic arresting of the flow of fuel to the burner, in case the pilot light thereof becomes extinguished, thereby to prevent flooding; and other objects as will be manifest from the following description.

I have chosen to illustrate my invention as embodied in an oil burner structure, involving as an element thereof a power device through the medium of which the supplying of the fuel to the burner is controlled, the fuel in this instance being oil and the power device an electric motor, a description of the accompanying drawings being as follows:

Figure 1 is a view in elevation, partly sectional, of an oil burner embodying my improvements. Figure 2 is an enlarged view in vertical sectional elevation of my improved thermostat and certain of the parts controlled thereby, the thermostat operating in connection with the pilot light for the burner, and the parts being shown in a position in which the supplying of fuel to the burner is arrested. Figure 3 is a section taken at the line 3 on Fig. 2 and viewed in the direction of the arrow. Figure 4 is a view like Fig. 2 showing the parts in the position they assume in the maintaining of the supply of fuel to the burner. Figure 5 is a section taken at the line 5 on Fig. 4 and viewed in the direction of the arrow. Figure 6 is a section taken at the line 6 on Fig. 4 and viewed in the direction of the arrow; and Figure 7, a view in sectional elevation of a furnace embodying my invention.

Referring to the particular illustrated installation in connection with which my improved thermostat mechanism is employed, the burner proper, represented at 7, is shown as mounted in the bottom wall 100 of a furnace 101 in position to extend at its upper end into the combustion chamber 102 of the furnace and discharge the fuel into the latter. The burner shown, which is of a type well known in the art, employs oil as the fuel the supplying of which to the outlet of the burner, from any suitable source

thereof through a pipe 8, is controlled by an electric motor 9.

Located adjacent to the burner structure referred to and in an opening 103 in the bottom wall 100 is a pilot light structure which discharges into the combustion chamber 102 and is provided for igniting the fuel issuing from the burner, this pilot light structure being represented generally at 10 and shown as involving a tubular member 11 carried by the main body of the burner and surmounted by a hollow cap 12 containing an opening 13 in its top, and a gas outlet tube 14 communicating at its lower end 70 with a gas passage 15 in the upper portion of a hollow supporting member 16 shown as supported at oppositely-facing slots 17 on headed studs 19 secured to, and depending from, outwardly-directed lugs 20 on the tubular member 11, the passage 15 communicating with a pipe 21 which leads to any suitable source of gas supply, as, for example, the ordinary service-supply pipes. The tube 14 extends centrally of the tubular member 11 and part way upwardly into the latter, as shown. When the gas flowing from the tube 14 is ignited a flame is produced which is caused to become contacted by the fuel issuing from the burner 7 for 85 igniting the fuel which thereafter burns at the burner 7 until the motor 9 is stopped.

The stopping and starting of the motor 9, for the purpose above stated, is controlled through the medium of a switch represented generally at 22 and controlled by a thermostat device cooperating with the pilot light. The switch device shown, and which is merely illustrative of one form of well known switch which may be employed, comprises a block 23 of insulating material located, and secured, in the hollow member 16, a pair of contacts 24 and 25 operatively connected in circuit with the motor 9 and operating, when bridged across by a current-conducting member, to close the circuit through the motor, a rocking bridging member 26 for the contacts 24 and 25 and an operating lever 27 for moving the member 26 into and out of bridging position. The 100 bridging member 26 is shown as formed of a shank 28 of insulating material having journaled in one end thereof a roller device 29 of current-conducting material which moves against the curved wall of an aperture 31 in the body 23 and which is movable into and out of engagement with the lower ends 110

of the contacts 24 and 25. A coil spring 32 surrounds the reduced end of the shank 26 and engages a washer 33 slidable on the shank lengthwise of the latter. The lever 27 is fulcrumed at 34 on a clip 35 secured to the insulating material of the body 23, the inner end of this lever being provided with a cross-pin 36 extending at opposite sides of the lever and together with the extremity 16 of the lever at which the pin 36 is located, extending into, and being movable lengthwise of, a slot 37 in the shank of the member 26. The construction of the switch is such that the rocking of the lever 27 on its pivot from the position shown in Fig. 2 to the position shown in Fig. 4, operates to cause the bridging member to assume the position shown in Fig. 4 in which position its bridging element 29 engages the contacts 24 and 25 and closes the circuit therebetween, and when this lever is reversely rocked from the position shown in Fig. 4 to the position shown in Fig. 2 the bridging member is moved to circuit-breaking position, represented in Fig. 2, it being understood that the spring 32 operates to cause the switch to function as a snap switch in the movement of the lever 27 in either direction to cause the pin 36 to swing through, and beyond the plane in which the fulcrum 34 of the lever, and the roller-bridging element 29 extends.

The lever 27 is operated through the medium of a vertically-reciprocable rod 38 containing a slot 39 into which the outer end of the lever 27 extends, this lever, which is located in the member 16, being pivotally connected, at 40, with the upper end of a link 41 the lower end of which is pivotally connected at 42 with the crank-arm 43 of a shaft 44 journaled in a wall of the member 16, the outer end of this shaft being equipped with an operating lever 45 into the path of movement of which, in the movement of the lever to the left in Fig. 2, a stop 46 on the member 16 extends, the throw of the lever 45 being such that upon swinging this lever in one direction or the other the switch will be opened or closed, depending upon the direction in which the lever is swung.

The thermostatic means hereinbefore referred to comprise the rod 38 which is connected at its upper end with a head 47, in the form of a disk which is centrally aperture, as represented at 48, and at which aperture it surrounds, and is vertically slidable on, the gas tube 14. The rod 38 is located to one side of the tube 14, as shown, and the head 47, at a point diametrically opposed to its connection with the vertically slidable on, the gas tube 14. The rod 38, is connected with the upper end of a coil spring 49, the lower end of which is connected with the supporting member

16, this spring operation to yieldingly resist upward movement of the parts controlled thereby from the position shown in Fig. 2. The head 47 is provided with upwardly-extending, spaced apart, thermostat bars 50 76 which are each formed of strips 51 and 52 of metal having different coefficients of expansion, the material of which the strips 51 are composed having a lower coefficient of expansion than the material composing 75 the strips 52. The bars 50, located respectively at opposite sides of the tube 14, extend upwardly beyond the upper extremity of the latter, these bars being shown as connected with the head 47 to move therewith, by means of a ring 53 surrounding the upper reduced portion 54 of the head 47, and pins 55 extending through said ring and bars and into the reduced portion 54 of the head. The upper extremities of the bars 50 terminate in outwardly-bent portions 56 adapted to cooperate with the upper ends of a pair of vertically-disposed rods 57 located within the member 11 and rising from, and rigidly secured at their lower ends, to the 80 supporting member 16, the head 47 being apertured at 58 to receive the rods 57 relative to which the head 47 is vertically movable. The parts just described are so constructed and arranged that when the structure comprising the head 47, bars 50, and rod 38 is raised to a position in which the shoulders 56 extend above the ends of the rods 57 and the bars 50 are subjected to the heat of the flame at the pilot, the bars will assume the 85 outwardly-deflected position represented in this figure, in which position their outwardly-extending shoulder portions 56 extend directly above and thus in alignment with the respective rods 57 and in interlocked 90 relation to the latter as shown in Fig. 4, due to the distorting effect on these bars produced by the unequal expansion of the strips 51 and 52 of which they are formed, these bars extending in such outwardly diverging condition as long as the pilot remains ignited. Upon the pilot becoming extinguished, these bars quickly return to a 95 position in which their projecting portions 56 are withdrawn out of alignment with the 100 respective rods 57, as shown in Fig. 2.

The operation of the structure shown is as follows: Assuming that the parts of the structure are in the position shown in Figs. 1, 2, and 3, in which the switch controlling the motor 9 is open and consequently no fuel is being supplied to the burner 7, the operator starts the burner by opening the pilot tube 14 to the supply of gas furnished through the tube 21, as by opening a valve 120 (not shown) interposed in the gas line and igniting the gas at this tube, and swinging the lever 45 to the left in Fig. 2 which results in the closing of the switch controlling the motor 9 which latter there- 125

upon starts into operation and supplies combustible fuel to the burner 7 which is ignited by the flame at the pilot light. In the movement of the lever 45, as stated, the 5 projecting portions 56 of the thermostat are moved above the upper ends of the rods 57, the operator holding the lever 45 in the position to which it was swung, as just stated, until the bars 50 have become sufficiently heated to effect their distortion to 10 a position in which their shoulders 56 overlap the tops of the rods 57, whereupon the rod 38, together with the parts carried thereby as hereinbefore described, lower to a 15 position in which the projecting portions 56 bear against the upper ends of the rods 57 as shown in Fig. 4 and continue to support the parts just referred to in a position in which the switch controlling the motor 9 20 remains closed. Should, however, the pilot light become extinguished, the thermostat bars 50, upon losing their heat, move inwardly at their upper ends, out of a position in which they engage the upper ends of the 25 rods 57, whereupon the rod 38, together with the parts connected therewith, is forced downwardly, by the action of the spring 49, to the position shown in Fig. 2, in this operation throwing the switch from the closed 30 position represented in Fig. 4 to the open position represented in Fig. 2. It will therefore be noted that provision is made for automatically preventing the supplying of fuel to the burner 7, unless the pilot 35 light is burning and the operator has positioned the thermostat as explained in connection with Fig. 4 of the drawings, and thus it is impossible to accidentally flood the burner with fuel.

40 By providing the thermostat mechanism as described the mechanism is caused to be capable of very quick action and is rendered very responsive in action. Furthermore, the device presents practically no time lag, 45 so that practically as soon as the pilot light becomes extinguished, the controlling circuit for the motor is opened.

The provision of the member 11 is of advantage inasmuch as it forms a shield 50 around the thermostatic element of the thermostat, protecting it against subjection to excessive heat produced in the combustion chamber 102 fired by the burner 7, the air in circulating through the member 11, due to 55 the forming of this member with openings at its upper and lower ends, also serving to prevent excessive heating of the thermostat bars 50. Furthermore the provision for the circulation of air through the member 11 60 and against the thermostat bars 50 effects quick cooling of these bars should the pilot light become extinguished.

While I have illustrated and described a particular construction embodying my invention, I do not wish to be understood as

intending to limit it thereto as the same may be variously modified and altered without departing from the spirit of the invention.

What I claim as new, and desire to secure by Letters Patent, is:

1. In a thermostatically controlled device the combination of a fuel-controlling device, and relatively movable members one of which is fixed, the movable one of said members comprising a flexible thermostatic element movable bodily and in its movements controlling said device, said thermostatic element being positioned to be heated and when heated engaging said fixed member for preventing movement of said thermostatic element, and when the supplying of heat thereto is discontinued disengaging from said fixed member to permit said thermostatic element to move for affecting the condition of said fuel-controlling device. 70

2. In a thermostatically-controlled device, the combination of a fuel-controlling device, and relatively movable members one of which is fixed, the other of said members being bodily movable independently of said device and in its movements controlling said device and positioned to be heated and when heated engaging said fixed member for preventing movement of said movable member, and when the supplying of heat thereto is discontinued disengaging from said fixed member to permit said movable member to move for affecting the condition of said fuel controlling device. 90

3. In a thermostatically-controlled device, the combination of a fuel-controlling device, relatively movable members one of which is fixed, the other of said members being bodily movable independently of said device and in its movements controlling said device and positioned to be heated and when heated engaging said fixed member for preventing movement of said movable member, and when the supplying of heat thereto is discontinued disengaging from said fixed member to permit said movable member to move for affecting the condition of said fuel controlling device, and means operating to move the movable one of said members when said last-referred-to member is released for movement. 100

4. In a thermostatically-controlled device, the combination of a fuel-controlling device, relatively movable members one of which is fixed, the other of said members being bodily movable independently of said device and in its movements controlling said device and positioned to be heated and when heated engaging said fixed member for preventing movement of said movable member, and when the supplying of heat thereto is discontinued disengaging from said fixed member to permit said movable member to move for affecting the condition of said fuel controlling device, and yielding means operat- 115 120 125 130

ing to move the movable one of said members when the latter is released for movement.

5. In a thermostatically-controlled device, the combination of a fuel-controlling device, and relatively movable members one of which is fixed, the movable one of said members being a flexible thermostatic element movable bodily and in its movements controlling said device, said thermostatic member having a shoulder extending crosswise thereof and said thermostatic element being positioned to be heated, and when heated interlockingly engaging at its shoulder with said fixed member for preventing movement bodily of said thermostatic element and when the supplying of heat thereto is discontinued disengaging at its shoulder from said fixed member to permit said thermostatic element 20 to move for affecting the condition of said fuel-controlling device.

6. In a thermostatically-controlled device, the combination of a fuel-controlling device, relatively movable members one of which is fixed, the movable one of said members being a flexible thermostatic element movable bodily and in its movements controlling said device, said thermostatic member having a shoulder extending crosswise thereof and said thermostatic element being positioned to be heated, and when heated interlockingly engaging at its shoulder with said fixed member for preventing movement bodily of said thermostatic element and 35 when the supplying of heat thereto is discontinued disengaging at its shoulder from said fixed member to permit said thermostatic element to move for affecting the condition of said fuel-controlling device, and 40 means operating to move said thermostatic member when the latter is released for movement.

7. In a thermostatic device, the combination of a thermostat member having a shoulder extending crosswise thereof, a second member extending substantially parallel with said thermostatic member, one of said members being fixed and the other thereof movable relative to said fixed member in the 45 direction of its length, and an element controlled by the movable one of said members, said thermostatic member when heated interlockingly engaging at its shoulder with said second member and preventing movement 50 of said movable member relative to said fixed member and when the supplying of heat to said thermostatic member is discontinued disengaging at its shoulder from said second member to permit movement of 55 said movable member.

8. In a thermostat device, the combination of a thermostat member comprising thermostatic elements in the form of bars each formed of strips of material having 60 different coefficients of expansion, a mem-

ber supporting said bars adjacent one end thereof, the bars at their other ends having oppositely outwardly directed projections, said bars when heated moving at their outer ends out of normal position, means tending to move said thermostat member in one direction, a member having portions adapted to be engaged by said projections when said bars are heated and holding said thermostat member against movement by said means and from which said projections disengage when the supplying of heat to said thermostat device is discontinued, to permit said means to actuate the latter, and an element controlled by said thermostat member. 80

9. In a thermostatically controlled device, the combination of a fuel-controlling device, and relatively movable members one of which is fixed, the movable one of said members comprising a plurality of flexible 85 thermostatic elements operatively connected together and movable bodily and in their movement controlling said device, said thermostatic elements being positioned to be heated and when heated independently engaging said fixed member for preventing movement of said thermostatic elements, and when the supplying of heat thereto is discontinued disengaging from said last-referred-to member to permit said thermostatic elements to move bodily for affecting the condition of said fuel-controlling device. 95

10. In a furnace, the combination of a combustion chamber, a burner therein, the bottom of said chamber containing an upwardly extending passage open at its opposite ends, said passage at its top being restricted thereby to form means shielding the interior of said passage from the heat in said chamber, a pilot burner for said first-named burner and located in said passage, and a thermostatic device controlling the supplying of fuel to said first-named burner, the thermostatic element of said device extending into said passage into the path of 100 the currents of air circulating therethrough. 110

11. In a furnace, the combination of a combustion chamber, a burner therein, an upwardly extending hollow member having its opposite ends open and opening at its upper end into the combustion chamber and at its lower end through the bottom of said combustion chamber, the opening at the top of said hollow member being restricted thereby to form means for shielding the interior of said hollow member from the heat in said chamber, a pilot burner for said first-named burner and located in said hollow member, and a thermostatic device controlling the supplying of fuel to said 115 first-named burner, the thermostatic element of said device extending into said member into the path of the currents of air circulating therethrough. 120

OSCAR C. SCHROEDER.
